200,200

TILE OR SIMILAR ARTICLE

Philip M. Brody, Scarsdale, and Frederic H. Rahr, New York, N.Y., assignors to Wood Conversion Company, St. Paul, Minn., a corporation of Delaware

Original design application Jan. 24, 1963, Ser. No. 73,305.
Divided and this application July 31, 1964, Ser. No.
81,096

Term of patent 14 years

(Cl. D18—2)

FIG. 1

FIG. 2

FIG. 1 is a front face view of a tile or similar article showing the new design of our invention;

FIG. 2 is an edge view of the tile of FIG. 1.

This application is a division of our original design application, Serial Number D. 73,305, filed January 24, 1963, and entitled "Tile or Similar Article."

We claim:

The ornamental design for a tile or similar article, substantially as shown and as described.
